A. CELLER

SOAP DISSOLVER AND AGITATOR

Filed June 17, 1922

UNITED STATES PATENT OFFICE.

ARTHUR CELLER, OF BROOKLYN, NEW YORK.

SOAP DISSOLVER AND AGITATOR.

Application filed June 17, 1922. Serial No. 568,987.

To all whom it may concern:

Be it known that I, ARTHUR CELLER, a citizen of the United States, residing at Brooklyn, in the county of Kings, State of New York, have made a certain new and useful Invention in Soap Dissolvers and Agitators, of which the following is a specification.

This invention relates to that class of mixers wherein soap is dissolved, and the contained water is quickly and uniformly charged with soap to any desired degree.

A further object includes the provision of a reticulated receptacle for receiving bars of soap, said receptacle being also provided with means for causing increased agitation when rotated. Another object includes the provision of simple and efficient means for holding the rotating receptacle in place by easily disconnecting means.

Other objects will appear hereinafter, and I obtain these objects by the device illustrated in the accompanying drawing, where—

25 Fig. 1 is a plan view.

Fig. 2 is a sectional view taken on lines 2—2 of Fig. 1.

Fig. 3 is an enlarged fragmentary plan view showing the releasable holder; and

30 Fig. 4 is a sectional view taken on lines 4—4 of Fig. 2.

Like numerals refer to similar parts throughout the several views.

In preparing soapy water for washing cars, dishes, clothes, and for other purposes, it has heretofore been customary to dissolve shaved soap or soap chips, or to use soap shakers for making soap-suds for the purpose of charging wash waters with soap. In place of these tedious and haphazard modes of procedure I provide a soap container 10 which is fitted to be rotated in a suitable receptacle 11, as a pail or equivalent means, to thereby supply the desired degree of soap to the water in the pail. This soap container has a dome shaped bottom 12, which is supplied with a boss 13 of proper construction to fit in a bearing 14. This bearing is fastened by rivets 15, or equivalent means, to the bottom 16, of the receptacle or pail and forms the lower anchor for the soap receptacle. A removable cover 17 fits frictionally into the soap container, and is provided with a shank or journal 18, which is squared at the end

to receive handle 19. In order to support or anchor the container at the upper end, the top of the pail has a hood 20 which is provided with doubled plates 21, and fitted with a slot 22, in which shank 18 is held by a movable hook 23, thus permitting the container to rotate freely, and to be quickly released, or fastened, by moving the hook in and out of engagement on its pivot 24. A spring 25 assists in holding the hook in position, and a boss 26 aids in moving the hook out of engagement.

The soap container is further provided with perforations 27 for permitting free access of water, and, in my preferred form, stirrers 28 assist in agitating the mixture. 70 A bail 29 may be provided for convenience in carrying.

From the drawing and description, the operation of my device will be readily understood. Bars of soap are put into the container. The cover is then closed. By opening the hook the container is readily placed into operative position as shown in Fig. 2, for example. By means of the handle the container is rotated, and the water in the 80 pail is quickly charged with the required amount of soap. The container may then be removed, or it may be permitted to remain in position, if desired. It is apparent that my device affords easy and efficient 85 means for quickly supplying the required amount of soap. It also affords means for stopping dissolution of soap at any time, and my device is herein also highly efficient 90 in saving soap as well as time.

Having now described my invention and given a specific application thereof, what I claim as new and useful and of my own invention, and desire to secure by Letters Patent is,—

1. In a soap dissolver and agitator, a liquid receptacle, an anchor device on the bottom thereof, a hood extending partly over the top thereof, said anchor device and hood being placed off center, and a soap container held in said anchor device and said hood and means to rotate said soap container to charge the liquid in said receptacle with dissolved soap to any desired degree.

2. In a soap dissolver and agitator, a liquid receptacle for holding liquids to be charged with soap, anchor devices on said receptacle, said anchor devices being placed

off center, and a cylindrical soap container mounted in said anchor devices for being rotated to charge the liquid with soap.

3. In soap dissolvers, a soap container, a liquid receptacle, an anchor plate fastened on the bottom thereof, a hood at the top of said receptacle and extending over said bottom anchor plate, said hood having a slot and means on said hood for rotatively holding said container in the slotted hood.

4. In soap dissolvers, a soap container, a bearing at the bottom and a journal shaped at the top of said container, a liquid receptacle having anchor devices off center, said anchor devices comprising a bottom anchor plate and a slotted hood having a spring tensioned hook for holding said container in rotative position.

5. In soap dissolvers, a soap container, a bearing at the bottom and a journal shaped at the top of said container, a liquid receptacle having anchor devices off center, said anchor devices comprising a bottom anchor

plate, a slotted hood, a hook on said hood, and a spring for holding said hook in closed position.

6. In soap dissolvers, a soap container, a bearing at the bottom and a journal shaped at the top of said container, a liquid receptacle having anchor devices off center, said anchor devices comprising a bottom anchor plate, a slotted hood, a hook on said hood, a spring for holding said hook in engaging position, and lateral extensions on the said container for agitating the contained liquid.

7. A soap container for soap mixers, comprising a cylindrical body provided with lateral perforations, external ribs on said body a bearing on the bottom of said body, a cover for the top of said body, said cover being provided with a shaft, and a handle on said shaft for operating said container.

In testimony whereof I have hereunto set my hand on this 12th day of June A. D., 1922.

ARTHUR CELLER.
